UNITED STATES PATENT OFFICE.

JOSEPH MENCHEN, OF SUMMIT, NEW JERSEY, ASSIGNOR TO P. A. B. ALARM & LOCK CORPORATION, OF WILMINGTON, DELAWARE, A CORPORATION OF DELAWARE.

FUSE MECHANISM.

Original application filed April 13, 1918, Serial No. 228,343. Divided and this application filed June 17, 1921, Serial No. 478,335. Renewed February 25, 1925.

To all whom it may concern:

Be it known that I, JOSEPH MENCHEN, a citizen of the United States, and a resident of Summit, in the county of Union and State of New Jersey, have invented a new and useful Fuse Mechanism, of which the following is a specification.

The invention relates to aerial torpedoes, to firing means therefor, and more particularly to the fuse mechanism for controlling the same, and to various features and aspects of such matters which will become apparent. Among the objects are to insure safety during handling and while on the plane and against failure to explode when dropped, to provide effective and readily adjustable means for timing the explosion, and to insure explosion in event of the bomb encountering either a substantially unyielding obstacle, such as a building, or a relatively yielding body such as another aeroplane or a Zeppelin or a net. The preferred embodiment of the invention will now be described, but it will be understood that various equivalent constructions may be devised. The subject-matter of the present application is a division of application Serial No. 228,343, filed April 13, 1918.

In the drawings:

Fig. 1 is a side elevation of one of the torpedoes in its carrying frame, the intermediate and major portions of the torpedo and frame being broken away for economy of space and dotted lines being used to illustrate the shifted position of the releasing parts;

Fig. 2 is a large sectional plan view of the rear end of the torpedo and of the cooperative parts carried by the torpedo, the body of the torpedo itself not being shown;

Fig. 3 is a rear sectional face view of the fuse-holder disk;

Fig. 4 is a horizontal section through the left-hand portion of Fig. 2;

Fig. 5 is a side elevation of the parts shown in Fig. 2 in the normal or carrying position and showing the timing mechanism in a shifted position, the body of the torpedo being omitted from the illustration;

Fig. 6 is a vertical longitudinal section through the same parts shown in the act of swinging downward with the torpedo, the body of which, however, is not shown;

Fig. 7 is a view showing the parts carried

by the torpedo dropping away from the fixture, a portion of the body of the torpedo being indicated by dotted lines;

Fig. 8 is a face view of the cap-holder and safety pin of the timing mechanism;

Fig. 9 is a detail view of the fuse.

The torpedoes are carried horizontally. The framework for supporting one of the torpedoes is seen more particularly in Fig. 1. From a member 2 forming part of the framework of the machine depends a fixed hanger-iron 3 braced by diagonal pieces 4. This hanger supports the rear end of the torpedo 5. The rear end of each torpedo is hinged or pivoted to its hanger 3, so that when its front end is released the torpedo swings down. The said forward end is supported and held by laterally spaced members 6 projecting downward from the part 2 and by a withdrawable rest 7, in the form of a lever. A front stem 8 on the torpedo is received between the members 6 and bears downward upon the lever 7, which is pivoted at 9 beneath one of the members and crosses the bottom of the recess between them, being movable in a horizontal plane away from the hanger 3 in order to release the bomb.

The supporting lever 7 is operated by a vertically disposed releasing hand lever 11, disposed adjacent the support 3 for the opposite end of the torpedo, the handle being within easy reach of the pilot. The hand grip of this lever is on its lower end, and its fulcrum pivot 12 is intermediate its ends, connecting it to a suitable hanger or fixed bracket 13. Its upper end is pivotally connected to one end of a slide 14, which is movable horizontally upon the upper part of the framework. The pivot pin 15 is guided in a horizontal slot 16 in the fixed structure, and the opposite end of the slide is provided with another guide slot 17 which slides upon a fixed pin 18. The fulcrum portion of the hand lever is preferably slotted, at 19, to allow for the difference in movement of the parts. The end of the slide remote from the hand lever has a downwardly extending part 20, to which the free end of the supporting lever 7 is connected, so that movement of the slide by the hand lever in the direction of the forward end of the torpedo withdraws

the rest for said end, permitting it to hinge downward on the hanger 3.

Upon the lower end of the hanger iron 3 is hinged a hollow member 21, which receives a rear stem 22 on the torpedo and constitutes a means for carrying and actuating a tripping or firing member 23. The pivoted end of this tubular member or holder is seen slotted at 24 to accommodate the hanger iron, and the two are connected by a transverse pivot pin 25. The torpedo stem 22 is connected to the holder, after being entered therein, by a shear pin 26, which is passed through registering holes in the parts. This connection is destroyed, and the torpedo consequently freed, by the power developed by the downward swinging of the torpedo, when its front end is released; and to this end the front edge of the extension of the hanger 3 below the hinge axis is formed as a cam or eccentric 27, the form and relation of which to the stem 22 are such that at a predetermined point in the downward swing, at or near the vertical position of the bomb, the rear end of the stem riding forcibly upon the fixed cam thrusts the stem downward and outward in the holder, thereby shearing off the pin 26 and permitting the torpedo to drop.

The constructions and arrangements for firing at the rear end of the torpedo involve important features of novelty. There is a detonator 31 capable of setting off the body of explosive in the interior. This detonator may be ignited by means of a time fuse 32, disposed circularly, that is to say in an arc, in a disk 33 forming part of a fuse-container secured on the rear end of the torpedo at the base of the stem 22. This container has an arcuate groove 34 in its front face, which communicates with the rear face by a series of definitely located flash ports 35. At the regions of these ports the covering of the fuse may be removed and quick match composition 32^a applied to insure the action of the fuse. One end of the groove 34 is connected by a radial groove 36 with a central opening 37, through which the fuse is led to the detonator 31. The fuse container is completed by another disk 33^a, also provided with a central opening, and which is screwed into a flange 71 on the front face of the disk 33, a plate 72 of vitreous material being preferably interposed between the two disks, closing the face of the groove 34. A flange 73 on the rear end of a copper tube 74 containing the detonator is also clamped between the disks 33 and 33^a of the fuse container, the detonator projecting forward through the central opening in the disk 33^a so as to enter the interior of the bomb. The stem 22 is united or secured in rearward projecting relation to the disk 33, and the disk 33^a has a central forwardly disposed threaded boss 75, whereby the entire unit may be

secured to the suitably recessed rear end of the torpedo.

On the lower or forward end of the hinged holder 21 is a timing head 38, which is also in the form of a disk of approximately the same diameter as the fuse container 33. When the torpedo is in the frame, these two parts are held face to face; and one of them is mounted rotatably. Preferably the head 38 is secured to the holder in such manner that it may be turned thereon without movement lengthwise. Tongue and groove formations 33^b, 38^b on the disks 33 and 38 serve to prevent entrance of water between them. The head 38 is cut away or recessed at one side, as at 39; and in this recess is a firing block 40 containing a cap seat 41 and a flash passage 42 to register with any one of the ports 35. The flash passage 42 terminates in a projecting nipple 43 on the forward or inner face of the rotatable head, adapted to enter said ports and to hold the parts in fixed relation when once adjusted. To permit of the adjustment the firing block bearing the nipple or registering projection is mounted on the timing head disk in such manner that it may yield away from the fuse container, while being normally pressed thereto. This is accomplished by connecting the end of the block 40 adjacent the center to the head 38 by means of a transverse pivot pin 44. An expansion spring 45 confined between the block and a bracket 46 on the head urges the block against the fuse container 33, or to a position in which the nipple will enter a port. The ports not in registry with the nipple at any time are covered by the timing head disk 38. A handle 47 projecting from the block 40 facilitates the turning of the head about the axis of the holder 21 and stem 22, and the movement of the block away from the fuse container to disengage the nipple. The nipple 43 is preferably located eccentrically with respect to the chamber of the flash passage, and the front or lower wall of this chamber is formed with a cavity 42^a having a vent opening 42^b, the cavity being in line with the cap 48, so that when the latter is fired its wadding will be caught in the cavity and will be prevented from obstructing the nipple.

The cap 48, which is placed in the seat 41 in the firing block, is fired by a hammer 49, the head of which is secured to the end of a flat spring 50, which in turn is secured to the bracket 46. The spring 50 is normally not under firing tension, so that there is no danger of its being accidentally released and flying against the cap; and in addition the cap is protected by a safety pin 51, which is inserted through holes in the block 40 over the cap in position to prevent the hammer touching the cap as long as the pin is in place. This pin may be in the form of a

cotter-pin with a large and conveniently accessible ring handle 51^a, and is held frictionally in place and may be readily withdrawn by the pilot before pulling the launching lever 11.

The hammer 49 is retracted and released by the tripping member 23 heretofore referred to as being mounted on and operated by the holder or hinged member 21. The said member 23 is desirably constructed as a collar slidably encircling the holder and having a rim 52 which contacts with the tip 53 of the hammer and draws the same rearward when the collar itself is drawn rearward or upward on the holder. Continuance of the movement carries the rim 52 from beneath the extremity of the hammer, and the latter is then driven by its spring against the cap 48. The movement of the tripping member upward and rearward on the holder is brought about as the result of the downward swinging of the holder and the connection of the tripping member with a fixed point above the hinge axis 25, the said connection being a pull link or pair of links 54, pivoted at 55 to the tripping member and at 56 to the hanger 3.

In addition to the time fuse firing mechanism just described, another firing member is provided at the rear, adapted to be actuated upon contact of the torpedo with a more or less yielding body. This second firing pin or plunger 57 is mounted to slide in the rear stem 22 and operates by inertia, which causes the plunger to continue downward against the resistance of a relatively weak spring 58, after the torpedo and its stem have been stopped in a more or less cushioned manner by encounter with a dirigible, an observation balloon, another plane or protective nets such as are placed over some buildings. The device will, of course, also operate in event of the bomb striking the earth or an unyielding obstacle. Normally the plunger 57 is barred against forward movement by a safety shear pin or screw 59, which passes through the wall of the stem 22 into the plunger. The rear portion or tail 60 of the plunger is extended past the shear pin 26, heretofore described and which it accommodates in a slot 61, and beyond the rear end of the stem 22, in position to be acted upon by the cam 27, in advance of the action thereof upon the stem, so that the screw 59 is sheared and the inertia plunger 57 released before the torpedo is freed from the hinge support. The said plunger acts upon a cap 62 in or adjacent the base of the stem 22, which cap is arranged to fire the detonator 31, to which the time fuse 32 also leads. As shown this cap is placed in a seat 62^a, which is screwed through the opening 37 of the disk 33, which is threaded for the purpose, into the interior of the stem, which is formed as a con-

tinuation of said opening and which is threaded for a short distance in rear of the disk. Air release holes 62^b are formed in the wall of the stem behind the cap so that forward movement of the striker will not be opposed by an air cushion.

In operation, each torpedo is carried horizontal as stated. The shear members 26 and 59 and the withdrawable safety pin 51 are all in place. To launch the torpedo and to place it in condition to explode, the aviator sets the timing head 38, draws out the pin 51 and pulls the lever 11. The latter operation moves the slide or longitudinally extending connection 14, and shifts the rest lever 7 from beneath the forward stem 8 of the torpedo. The torpedo immediately swings down upon its rear hinge support, and this movement actuates the link-held tripping member 23 in the manner already described. The hammer 49 is pulled back and let go, and thereupon drives forward upon the cap 48 which is fired, its flame striking through the passage in the block 40 and through the registering port 35 to the time fuse 32, which it ignites. This occurs before the pin 26 is sheared and while the torpedo is still connected to the hinge support. Also, before the said connection is broken, the shear member 59 is destroyed by the coaction of the plunger 57 and the cam 27, so that this inertia firing member is free to act upon contact to explode the detonator 31, if at that time it has not already been set off by the time fuse. Finally, the pin 26 is sheared and the torpedo drops away, with its time fuse burning and its impact firing devices in condition to operate. When the torpedo falls from the plane it carries the fuse container with it, but the timing head is left behind upon the hinge fixture, of which it forms a part.

In order to set the time fuse to explode at any height the operator merely tilts the block 40 away from the fuse container 33 and turns the timing head 36 by means of the handle 47 until a pointer 63 cooperating with index marks 64 indicates the desired elevation. Then the handle is released and the firing block snaps into registry with one of the flash ports 35. In case the aviator intends the torpedo to explode only upon contact, he can turn the head 38 so that the flash port 42 is opposite a blank portion of the fuse-holder disk 33, in which event the fuse will not be ignited.

I claim:

1. In an aerial torpedo, the combination of a detonator in the rear portion of the torpedo, a central stem projecting rearward from the torpedo, inertia firing means in said stem substantially in line with the detonator, a time fuse disk at the base of said stem having its face provided with a circularly disposed series of flash ports, and a

rotatable timing head covering the ported face of said disk and having means for igniting the fuse at one or other of said ports.

2. In an aerial torpedo, the combination 5 of a detonator in the rear portion of the torpedo, a central stem projecting rearward from the torpedo, inertia firing means in said stem substantially in line with the detonator, a time fuse disk at the base of said 10 stem having its face provided with a circularly disposed series of flash ports, a cover disk, a firing block mounted yieldingly in the cover disk, and a spring hammer cooperative with the firing block, the time fuse disk 15 and cover disk being relatively rotatable, and means for registering the firing block with any of the flash ports.

3. A fuse container for aerial torpedoes comprising two disks secured together, the 20 front disk having means of securement to the rear end of a torpedo and the rear disk having an arcuate series of flash ports leading from its rear face to a curved fuse channel within, and a detonator tube projecting 25 centrally forward from the fuse container and having its rear end held between the disks.

4. A disk-like fuse container having 30 means of securement to the rear end of an aerial torpedo and formed with a central opening, an internal arcuate fuse channel having a series of flash ports opening through the rear face and an extension leading to the central opening, and a forwardly 35 projecting detonator tube held in said opening.

5. A disk-like fuse container having a central opening and means of securement to the rear end of an aerial torpedo, a central forwardly projecting detonator carried by the 40 fuse container, a circularly disposed time fuse in the container leading to the central opening, a hollow stem carried by the fuse container in rearward projecting relation, a cap seat in line with the central opening, 45 and an inertia firing device in the stem in rear of the cap seat.

6. In an aerial torpedo, a disk-like fuse container on the rear end of the torpedo having a central opening, a detonator disposed 50 forwardly in line with said opening, a circularly disposed time fuse in the container leading to said central opening, a hollow stem projecting rearward from the container, a cap seat, and an inertia firing device in said stem. 55

7. In an aerial torpedo, a disk-like fuse container on the rear end of the torpedo having a central opening, a detonator disposed forwardly in line with said opening, 60 a circularly disposed time fuse in the container leading to said central opening, a hollow stem projecting rearward from the container, a cap seat, and an inertia firing device in said stem, 65 said fuse container having a curved series of flash ports in its rear face, in combination with a timing head rotatable about the axis of the stem and having means for igniting said fuse through any of the flash ports.

JOSEPH MENCHEN.
